G. B. RATTERMAN

STAND FOR ELECTRIC IRONS

Filed Nov. 28, 1922

George B. Ratterman
INVENTOR

E. G. Siggars

ATTORNEY

UNITED STATES PATENT OFFICE.

GEORGE B. RATTERMAN, OF NEW YORK, N. Y.

STAND FOR ELECTRIC IRONS.

Application filed November 28, 1922. Serial No. 603,835.

To all whom it may concern:

Be it known that I, GEORGE B. RATTERMAN, a citizen of the United States, residing at New York city, in the county of New York and State of New York, have invented new and useful Improvements in Stands for Electric Irons, of which the following is a specification.

My invention relates to a stand adapted for supporting electric irons and the like, which is provided with a switch for automatically controlling the current through the iron as may be desired.

The principal objects of the invention are to provide means for supporting the implement which will insure safety against fire, as well as preventing accidents which are likely to cause injury to the implement; and to provide a practical device for supporting the implement when not in use, which has a self-contained means operable by gravity for shutting off the current when the implement rests thereon, thus insuring economy as well as safety.

The invention will be described in connection with the accompanying drawing which illustrates the preferred structure by means of which the principles of my invention may be embodied.

In the drawing:—

Fig. 1 is a plan view of the invention.

Fig. 2 is a similar view with a portion of the supporting member removed.

Fig. 3 is vertical section taken on the line 3—3 of Fig. 1.

Fig. 4 is a vertical section taken on the line 4—4 of Fig. 1.

Fig. 5 is a detail view of the terminals secured to the pivoted supporting element.

The invention comprises a rectangular hollow base or tray 1 having its side walls rabbeted at the upper inside edge to form shoulders 2. The shoulders of the two opposed sides of the base are formed with alined grooves 3 forming bearings for a transverse pivot rod 4, on which is supported a supporting element or platform 5, the same being connected with the pivot rod by ears 6 or similar attaching means. The uppermost portion of the pivot rod 4 is somewhat above the plane of the shoulders 2, so that the platform 5 has a limited rocking movement.

One side of the base is provided beneath the platform with a socket 7 which may be connected by suitable connecting wires 8 to

a source of electric current. The socket 7 has electric connections 9 with a pair of terminals 10 located in the bottom of the tray near one end thereof. The opposite side of the tray is provided with an electric socket 11 which is connected by wires 12 with spring terminals 13 secured to the under side of the platform 5 vertically above the first-mentioned terminals 10. The socket 11 may be connected, by suitable electric conductors 14, with an electric sad iron 15, or other implement of a similar nature. In some instances, it may be also be desirable to connect the socket 11 with electric conductors 16 which may lead to a signal light 17 located at any suitable point.

It will be noted that the pivot rod 4 is located at one side of the transverse center of the stand so that the center of gravity of the platform 5 will be located at one side thereof, and normally, the terminals 13 and 10 will be held in contact with each other by the weight of the platform. The relative weight of the platform and the iron 15 is such, however, that when the latter rests upon the short end of the platform, the weight thereof will be overbalanced and the contact between the terminals will be broken. The surface of the platform is provided with suitable indicia, as shown at 18 and 19, indicating where the iron may be placed to have the current on or off.

The platform 5 may be composed of any suitable insulating material which is also a poor conductor of heat, such for example, as asbestos. When it is desired to use the iron with less heat than would be generated by leaving the current on, the platform 5 may be locked in off position by means of a clip 20, which is pivoted to the end of the tray, as shown in the drawing. The platform 5 is also preferably provided with an upstanding peripheral flange 21 to prevent the iron from accidentally slipping off or being pushed off from the platform.

From the foregoing description, it will be appreciated that the invention is primarily a safety device. Whenever the person using the iron wishes to set it down, he can do so without danger of causing fire or damaging the surface on which it rests. At the same time, he will ordinarily set it on the off end of the platform, thus automatically disconnecting the current, which results in greater economy. If, however, the iron is allowed to remain long enough to get too cold, it may

be easily pushed to the other end of the platform, whereupon the current will be immediately turned on again. The flange on top of the tray also prevents many accidents which are likely to result in breakage of the rheostat or the wires leading thereto. The lock 20 may be very conveniently used without turning the switch at the chandelier.

While I have shown specifically one form 10 in which my invention may be embodied, it will be readily understood that various modifications may be made therein, without departing from the principles of the invention as defined by the claims. It will also be 15 understood that any number of these stands may be connected up into one system and be connected to one signal light.

What is claimed is:—

1. The combination of a base having a 20 pair of terminals adapted to be connected to a source of electric current, a support pivoted to said base and having terminals vertically over the first-named terminals and adapted to be connected to an electrically 25 heated implement, the center of gravity of said support being between the pivot and the terminals whereby the latter will be normally held in contact by gravity, the weight of the implement being sufficient to swing 30 the support and break the contact when the implement is placed on the side of the support remote from the terminals, and means for locking the support in its "off" position regardless of the position of the implement.
- 35 2. The combination of a base having a pair of terminals adapted to be connected to a source of electric current, a support pivoted to said base and having a peripheral upstanding flange within which an electrically 40 heated implement may be supported, said support having secured to its under side electric terminals located vertically over the first-named terminals and adapted to be connected to the implement, the center of gravity 45 of said support being between the pivot and the terminals whereby the latter will be normally held in contact by gravity, the weight of the implement being sufficient to swing the support and break the contact 50 when the implement is placed on the side of the support remote from said terminals, and a locking device located at one side of

the platform pivot for holding the terminals on the platform out of contact with the terminals in the base.

3. The combination of a hollow base having a pair of terminals adapted to be connected to a source of current, a pivot rod extending transversely within said base, a supporting platform pivotally mounted 60 thereon and having a peripheral upstanding flange within which an electrically heated implement may be supported, said platform having on its underside terminals located vertically over the first-named terminal and 65 adapted to be connected to the implement, the platform being marked "On" at one side of the pivot, and "Off" at the other side thereof, said platform being normally operable by gravity to form a contact between 70 the pairs of terminals but operable by the weight of the implement when placed on the "Off" side to break said contact, and means for positively locking the platform with the terminals out of contact regardless of the 75 position of the implement.

4. The combination with a hollow base having shoulders on the inside at a point below the top thereof, of a platform, means for pivoting the platform to the base above 80 the plane of said shoulders, a pair of terminals connected to a source of electricity and arranged within the base; other terminals connected to the underside of the platform and arranged above the first-named terminals, and a locking device located at one side 85 of the pivot of the platform for holding the terminals on the platform out of contact with the terminals of the base.

5. The combination with a hollow base, of a tilting platform, means for pivoting the platform to the base at the top so as to move within the same, terminals carried by the base and connected to a source of electricity, other terminals carried by the platform and 90 adapted to make contact with the first-named terminals, and a locking device located at one side of the pivot of the platform for holding the terminals out of contact.

In testimony that I claim the foregoing 100 as my own, I have hereto affixed my signature.

GEORGE B. RATTERMANN.
